RADIO ANTENNA

Lawrence W. Stinson, Tulsa, Okla., assignor to
Raymond M. Wilmotte, Washington, D. C.

Application March 4, 1944, Serial No. 525,079

5 Claims. (Cl. 250—33.53)

1

This invention relates to a system or method of supplying auxiliary circuits and services to insulated-base radiating structures, and for electrical protection of such structures.

It applies particularly to radio towers, insulated from the ground, whose primary function is to carry and/or radiate energy at radio frequency, and which are of sufficient height from the ground level to the top of the tower to require or to be used for functions auxiliary to its primary function, such as other mechanical or electrical services.

In antenna towers insulated at the base, such as are commonly used in broadcasting, there has often been need to provide auxiliary services at power frequencies, such as 60 cycles. It has been customary to bring these auxiliary services into the tower structure through blocking chokes or transformers which provided no direct conductive path to ground, because of the need to avoid short-circuiting the insulator at the tower base. This invention provides such a direct and straight conductive path to ground without short-circuiting the tower base insulator.

It is one object of this invention to install low frequency alternating current or direct current circuits, very high or ultra-high frequency electric transmission lines, and/or other auxiliary services on antenna towers, without substantially impairing the radiating efficiency of the antenna at its operating frequency.

It is another object of this invention to provide, simultaneously and coincidentally, a low impedance path to the ground for escape of unwanted, wave-distorting, even-numbered harmonics of the operating frequency, and possible non-harmonic oscillations of frequencies close to such even-numbered harmonic frequencies.

It is yet another object of this invention to provide, simultaneously and coincidentally, a low impedance path to the ground for continuous dispersion of atmospheric static electric charges and to preclude or minimize the danger of equipment damage and/or service stoppage due to lightning discharges through the tower.

The following description, referring to the accompanying drawings, shows the method of installation and the relation of component parts upon which this invention is based:

Figures 1 and 2 show the invention applied to guyed radio antenna towers insulated from ground, and

Figure 1a is a schematic view of an insulated multiple-leg antenna tower.

In Figure 1, reference numeral 1 designates

2

the conductive tower structure, which serves as the antenna, such as may be used for amplitude modulation broadcasting service. This antenna structure is supported on base insulator 2 and concrete base 3 and maintained in position by guy wires 4, which are insulated from the ground and the antenna by strain insulators 5, or the position of the leg base may be maintained by anchoring it to an anchored base insulator 2 in the case of a multiple-leg fabricated tower structure as shown in Figure 1a. Numeral 6 indicates the electrical coupling circuit to a radio broadcasting transmitter, which supplies energy to the antenna at amplitude modulation frequency. Numeral 7 shows a conductive shielding conduit, containing tower lighting circuit 8, direct current or power frequency alternating current, which supplies electric code beacons 9 and/or electric tower lights 10, and a very high frequency transmission line 11, as might be required for radiating from frequency modulated antenna 12 at the top of the tower. I have found that this very high frequency is sufficiently high so that it does not affect transmission at amplitude modulation frequencies. The conductive shielding conduit 7 is supported on standoff insulators 13 and is connected to lower junction box 13, which is connected to earth adjacent to or beneath the tower by an electric conductor of practically zero impedance, and is also connected to upper junction box 14, which is connected to the conductive tower structure by an electric conductor of practically zero impedance. The conduit 7 may be located inside the tower. This upper junction box 14 is located at approximately a quarter wavelength of the antenna broadcasting frequency above the ground level. The conductive shielding conduit may comprise several conduits in parallel, connected electrically at frequent intervals between the lower junction box 13 and the upper junction box 14.

Figure 2 shows a broadcasting tower comprising several conductive segments 1a, 1b, etc., separated by insulators 2b, 2c, etc., and insulated from the ground by base insulator 2a, the bottom segment 1a being less than a quarter wavelength high. It is evident that segment 1a alone may constitute the antenna radiator. In either case the tower structure is supported on base insulator 2a and concrete base 3 and maintained in position by the means shown in Figure 1. Numeral 6 shows the electric coupling circuit to a radio broadcasting transmitter, which supplies energy to the antenna at amplitude modulation frequency. Numeral 7a shows a conductive shield

ing conduit, containing auxiliary electric and/or other circuits and services similar to those shown in Figure 1. This conductive shielding conduit 7a is connected to a directly grounded lower junction box 13 and runs up the conductive tower structure 1a on standoff insulators 17 to junction box 14, which is connected to the conductive tower structure by an electric conductor of negligible impedance. The length of the conductive shielding conduit 7a from lower junction box 13 to upper junction box 14 is extended to approximately a quarter wavelength at the antenna operating frequency, by suitably bending the conduit. The return conductor of the quarter wavelength line comprises the portions of conductive tower structure adjacent to conductive shielding conduit 7a. The impedance across the gap between the lower end of this conductive conduit and the base of the tower is very high at operating frequency, but practically negligible at even-numbered, higher harmonics of operating frequency.

Where the tower consists of several insulated conductive segments, superposed, the auxiliary services may be carried from one segment to another by installing a second section of conductive shielding conduit 7b from lower junction box 15 to upper junction box 16. The junction boxes 15 and 16 are conductively connected to, or near, the tops of tower legs 1a and 1b, respectively. The length of the conductive shielding conduit 7b from junction box 15 to junction box 16 is made approximately a quarter wavelength of the antenna operating frequency and thus maintains a very high impedance across the gap between its lower end and the lower end of tower leg 1b at antenna operating frequency, and a very low impedance across that gap at even-numbered higher harmonics of that frequency. The conductive shielding conduit may comprise several sections, in series, providing that each pair of adjacent conduit ends are connected by an electric conductor of negligible impedance, that the length of the combined sections shall be an odd multiple, including 1, of a quarter wavelength of the antenna operating frequency, and that the outer end of the final section is connected by an electrical conductor of negligible impedance to a conductive tower structure of length equal to that of the combined sections of conductive shielding conduit.

It has been found that when a pair of parallel conductors, one of which may be the tower itself, approximating in length any odd multiple, including 1, of a quarter wavelength of the operating frequency, and shorted at the further end, is energized with alternating current, there is developed at the open end an impedance sufficiently high to block effectively the leakage of energy at the operating frequency for which the tower is used as a radiator. At frequencies higher than the operating frequency this open end impedance is reduced and becomes a minimum for even-numbered harmonics of the operating frequency.

Referring to Figure 1, the operation of the combined equipment is as follows: Electrical energy is supplied at amplitude modulation frequency through electrical coupling circuit 6 from the radio transmitter to the antenna 1. Electrical energy, through circuit 8, for tower lighting units 9 and 10, and very high frequency through transmission line 11, for frequency modulation antenna 12, and also other possible services, not necessarily electrical, are supplied to the

antenna 1 through the conductive shielding conduit 7. The potential at operating frequency, established in the antenna 1 through transmitter coupling circuit 6, is impressed across the gap at the lower end of the quarter wavelength pair of parallel conductors, comprising the conductive shielding conduit 7 and the tower leg 18. This quarter wavelength line presents a high impedance across the gap between the base of the tower and ground and thus serves to block energy leakage from the antenna to ground at the antenna operating frequency. The continuous low impedance path formed by the tower structure from its top through junction box 14, through conductive shielding conduit 7, through junction box 13 to ground, offers easy means for leakage of energy from even-numbered wave-distorting harmonics of the operating frequency, also an easy means for dispersion of atmospheric static charges in the vicinity of the antenna, as well as a favorable path for high frequency lightning discharges to the earth through the tower structure.

Referring to Figure 2, the operation of the combined equipment there shown is as follows: Electrical energy is supplied at amplitude modulation frequency, through electrical coupling circuit 6 from the radio transmitter to the antenna 1a, 1b, etc. Any suitable coupling, not shown, might be used between segments 1a and 1b. Electrical and/or other auxiliary services are supplied to the antenna 1a, 1b, etc., through the conductive shielding conduits 7a, and/or 7b, etc. The potential at operating frequency, established in the antenna 1a, 1b, etc., through transmitter coupling circuit 6, is impressed across the gaps at the lower ends of the two quarter wavelength pairs of parallel conductors comprising, first, conductive shielding conduit 7a, between junction boxes 13 and 14, and conductive tower structure 1a, between base insulator 2a and junction box 14 and, second, conductive shielding conduit 7b, between junction boxes 15 and 16, and conductive tower structure 1b, between base insulator 2b and junction box 16. This creates very high impedances across base insulator 2a and tower insulator 2b. These high impedances serve to block energy leakage from antenna to ground at antenna operating frequency. The continuous low impedance path formed by conductive tower structure 1b, through junction box 16, through conductive shielding conduit 7b, through junction box 15, through conductive tower structure 1a, through junction box 14, through conductive shielding conduit 7a, through junction box 13 to ground, offers easy means for escape of energy from unwanted, wave-distorting, or apparatus destroying frequencies higher than antenna operating frequency.

While this invention has been pictured and described in detail in connection with its application to several kinds of radiating tower designs, it is not intended to limit its application to these particular designs, and it is to be understood that the invention applies also to other arrangements, where the same results are to be achieved by the same means, without exceeding its scope.

I claim:

1. In combination, a conductive antenna structure, less than a quarter wavelength in height, insulated from the ground, used at a predetermined radio frequency, a conductive shielding conduit carrying an auxiliary service to the antenna structure, a low impedance bond between the upper end of said conduit and an adjacent

point on the said conductive antenna structure, and a low impedance connection to earth at the lower end of said conduit, said conduit being suitably bent so that the distance between said low impedance bond and said low impedance connection to earth, measured along said conduit, is approximately a quarter wave-length for the said predetermined radio frequency.

2. In combination, a conductive antenna structure, comprising several superposed conductive segments, insulated from the ground and insulated between the top of each conductive segment and the base of the superposed conductive segment, used at a predetermined radio frequency, a first conductive shielding conduit carrying an auxiliary service to the bottom conductive segment, a low impedance first bond between the upper end of said first conduit and an adjacent point on the said bottom conductive segment, a low impedance connection to earth at the lower end of said first conduit, the distance between said first low impedance bond and said low impedance connection to earth, measured along said first conduit being approximately a quarter wavelength for the said predetermined radio frequency, a second conductive shielding conduit carrying said auxiliary service to a second said conductive segment of the antenna structure, a second low impedance bond between the upper end of said second conduit and an adjacent point on the said second conductive antenna segment, a second low impedance connection for the lower end of said second conduit to an adjacent point on the bottom conductive antenna segment, the distance between said second low impedance bond and said second low impedance connection being approximately a quarter wavelength for the said predetermined radio frequency.

3. In combination, a conductive antenna structure, insulated from ground, and used at a predetermined radio frequency, an auxiliary antenna supported by the antenna structure, means including an outer conductor for energizing the auxiliary antenna at a frequency higher than the said predetermined frequency, said outer conductor having a connection to the antenna structure and a connection to earth, the distance between the said connections measured along the outer conductor being approximately a quarter wavelength for the predetermined frequency, said conductor being adjacent and external to the antenna structure from its first mentioned to its second mentioned connection the cross-section of said

conductor being small compared to the cross-section of said antenna structure, whereby an external path to ground is provided for lightning without substantially decreasing the radiation resistance of the said conductive antenna structure.

5. In combination, a conductive antenna tower, means for insulating the antenna tower from the ground, means for impressing radio frequency voltages between the antenna tower and ground, means for supplying an auxiliary service to said antenna tower including a conductor connected to the antenna tower and ground at points substantially an odd number of quarter wave-lengths apart measured along said conductor, said conductor being external and closely adjacent to said tower between said points the cross-section of said conductor being small compared to the cross-section of said tower, whereby an external path to ground is provided for lightning without substantially decreasing the radiation resistance of said tower.

20 4. In combination, an antenna tower having corner legs, an insulator between said antenna tower and ground, means for supplying energy at a radio frequency to the antenna tower, means for supplying electric power at another frequency to said antenna tower including a conductor external to the antenna tower having connections to the antenna tower and to ground, said connections having a low impedance at the said radio frequency and being spaced from each other substantially an odd number of quarter wave-lengths, said conductor and one of said corner legs forming a pair of substantially parallel conductors in close electrostatic relation throughout the distance between said connections.
